United States Patent Office.

SAMUEL MCCLAIN, OF PHILADELPHIA, PENNSYLVANIA.

Letters Patent No. 61,846, dated February 5, 1867.

WHISTLE AND BIRD-CALL.

The Schedule referred to in these Letters Patent and making part of the same.

TO ALL WHOM IT MAY CONCERN:

Be it known that I, SAMUEL MCCLAIN, of the city of Philadelphia, in the county of Philadelphia, and in the State of Pennsylvania, have invented an improved Whistle and Bird-Call; and I do hereby declare that the following is a full, clear, and exact description thereof, reference being had to the accompanying drawings and to the letters of reference thereon marked.

The nature of my invention consists in constructing an instrument to emit sounds in imitation of birds, animals, &c., at the will of the performer, as will more fully hereinafter appear.

To enable those skilled in the art to make and use my invention, I will describe its construction and operation. In the drawings—

A A are pieces of morocco leather, or other suitable material, cut in the shape shown in Figures 1 and 2, or any other convenient form. These pieces are intended for the purpose of holding the piece of thin skin, bladder, or other similar material, (its form being shown at Figure 3,) between the teeth, and also assisting in part to keep the teeth from touching, but more particularly to cause a slight separation of the lips, forming an aperture for the emission of the breath. Figure 4, C, is a piece of tin, or any substance that will answer its purpose of giving stiffness to the leather, and prevent the teeth of lower jaw locking with those of the upper, it thus causes an opening through which the breath may be forced. The piece B is placed between the two pieces A, and the edges are sewn or fastened together; then the piece C is secured in like manner, in the position shown in Figure 5.

Before operating the "call," it should be soaked in water until it is soft, which will not be longer than five minutes. Now place the instrument or "call" with its curved edge in the mouth, far enough in for the teeth of the performer to rest upon the piece C, when the "call" is ready or in position. Begin breathing easily through the opening between your teeth over the exposed part of piece B, (marked b, fig. 2,) from the vibrations of which the sounds are produced; gradually increase your breathing force until you have reached the utmost of your power; you will by so doing acquaint yourself with the various notes or octave of the "call." Breathing slowly or quickly produces long or short notes. By pressing or closing the teeth with force, a high note is given out; releasing the pressure, a low note. After a little practice, a person who has a little taste for music, and is a tolerable mimic, can imitate all sounds, from the deep grunt of the swine to the shrill chirp of a week-old chick. The power of the instrument is only limited by the perfectness of the ear or taste for music of the performer, and his perseverance.

Having thus fully described my invention, what I claim as new, and desire to secure by Letters Patent, is—

The construction and arrangement of pieces A A B and C, substantially in the manner and for the purpose set forth.

In testimony that I claim the above-described "improvements in whistles and bird-calls," I have hereunto signed my name this 9th day of August, 1866.

SAMUEL MCCLAIN.
